tions coming within the scope of the invention as defined in the appended claims.

Having thus described our invention, what we claim as new, and desire to secure by United States Letters Patent is:

1. An animal trophy cutout, comprising a flat body piece for pasting on a flat wall, a tubular-like sheet neck piece for connection with said body piece, and a flat head piece for connection with said neck piece, said neck piece being connected with the body piece with lugs, said head piece being pivotally connected with the neck piece by a single bottom lug, and said head piece having lugs frictionally engaging through slots formed in the sides of said neck piece.

2. An animal trophy cutout, comprising a flat body for pasting on a flat wall, a tubular-like sheet neck piece for connection with said body piece, a flat head piece disposed on said neck piece, means pivotally connecting the bottom of said head piece to the bottom of said neck piece, and means for adjustably connecting the top corners of said head piece to adjacent areas of said neck piece for holding said head piece in desired pivoted positions about said bottom pivotal connection.

3. An animal trophy cutout, comprising a flat body for pasting on a flat wall, a tubular-like sheet neck piece for connection with said body piece, a flat head piece disposed on said neck piece, means pivotally connecting the bottom of said head piece to the bottom of said neck piece, and means for adjustably connecting the top corners of said head piece to adjacent areas of said neck piece for holding said head piece in desired pivoted positions about said bottom pivotal connection, said first means, comprising a lug formed on the bottom of said neck piece and secured to the back of said head piece adjacent the bottom thereof.

4. An animal trophy cutout, comprising a flat body for pasting on a flat wall, a tubular-like sheet neck piece for connection with said body piece, a flat head piece disposed on said neck piece, means pivotally connecting the bottom of said head piece to the bottom of said neck piece, and means for adjustably connecting the top corners of said head piece to adjacent areas of said neck piece for holding said head piece in desired pivoted positions about said bottom pivotal connection, said first means, comprising a lug formed on the bottom of said neck piece and secured to the back of said head piece adjacent the bottom thereof, said latter means, comprising lugs extending rearwards from the back face of said head piece and each being frictionally engaged through pairs of slits formed in adjacent areas of said neck piece.
5. An animal trophy cutout, comprising a flat body for pasting on a flat wall, a tubular-like sheet neck piece for connection with said body piece, a flat head piece disposed on said neck piece, means pivotally connecting the bottom of said head piece to the bottom of said neck piece, and means for adjustably connecting the top corners of said head piece to adjacent areas of said neck piece for holding said head piece in desired pivoted positions about said bottom pivotal connection, said first means, comprising a lug formed on the bottom of said neck piece and secured to the back of said head piece adjacent the bottom thereof, said latter means, comprising lugs extending rearwards from the back face of said head piece and each being frictionally engaged through pairs of slits formed in adjacent areas of said neck piece.
